ELEVATOR DISPATCHING SYSTEM

William F. Eames, Pittsburgh, Pa., assignor to
Westinghouse Electric Elevator Company, Jersey City, N. J., a corporation of Illinois

Application November 6, 1937, Serial No. 173,193

10 Claims. (Cl. 177—336)

My invention relates to dispatching systems for a group of elevators and more particularly to a mechanism for regulating the timing of the interval at which the cars are signalled to leave the dispatching floors.

One object of my invention is to so regulate the signals for dispatching elevators from a given floor that on the average a predetermined number or fractional number of elevators will be found standing at the floor.

Another object of my invention is to automatically regulate the timing of the interval so that the most efficient service from the bank of cars will result.

Another object is to have the arrival and departure of the cars from a given floor regulate the interval timing of the dispatcher.

A further object is to shorten the interval automatically when traffic conditions tend to accumulate more cars at a given floor than is found necessary for best service to the other floors.

A still further object is to lengthen the interval automatically if fewer cars are found at a given floor than is found necessary for best service at that floor.

For a better understanding of the invention, reference may be had to the accompanying drawings in which:

Figure 1 is a diagrammatic representation of a group of elevators embodying my improved dispatching system.

Fig. 2 is a top plan view of the dispatching timer embodied in the system shown in Fig. 1.

Fig. 3 is a top plan view of the motor driven rheostat for controlling the speed of the motor of Fig. 2.

Fig. 4 is a straight line drawing of the circuits for the dispatching system shown in Figs. 1 to 3; and

Fig. 4A is a diagrammatic representation of the relays and associated contact members embodied in Fig. 4.

The illustration of the relays in Fig. 4A shows them with their coils and contact members disposed in the same vertical positions they occupy in Fig. 4. By placing Fig. 4A beside Fig. 4, any contact or coil may be readily located in Fig. 4 by following a horizontal line across from its position in Fig. 4A. Fig. 4A is a key to the coil position and to the kind of contacts, the position and number associated with any given coil of Fig. 4.

For convenient reference the main relays and 55

parts are indicated in the drawings by the following reference letters:

B	—Interval adjusting relay.
1C to 4C	—Terminal relays.
5: F	—Flicker relay.
HL	—Limit switch for rheostat motor.
I	—Interval relay.
LL	—Limit switch for rheostat motor.
1N to 4N	—Next signal relays.
1R to 4R	—Sequence relays.
1S to 4S	—Start signal relays.
SS	—Stop sequence relay.
T1 to T3	—Timer contacts.
TS1 to TS4	—Terminal switch contacts.

15 Referring more particularly to the drawings, in Fig. 1, I have shown four cars 1E, 2E, 3E and 4E serving five floors. It will be evident that my system can be used with any number of cars or floors. Duplicate installations may be made at other than the lowest floor and the arrival and departure of the cars from this floor can be regulated independently of the action occurring at the lowest floor or any other floor. Switches 20 TS1 to TS4 shown in this case at the lowest floor are operated by a cam 8 on each of the various cars. The dispatching mechanism to be described is usually located in the pent house (not shown) and it operates signals 1L to 4L to advise 25 the operators of the respective cars the proper time to leave the dispatching floor.

Fig. 2 shows a plan view of a timing mechanism that may be used in my invention. An adjustable speed motor 24 drives shaft 22a 30 through a speed reducing gear 22. Mounted on shaft 22a are three cams 17—19 and 21. The angular position of cam 17 is adjustable with respect to the positions of cams 19 and 21 for a purpose that will be explained. The cam parts 35 operate on rollers 16, 18 and 20 to open or close contacts T3, T2 and T1 respectively once for each revolution of the shaft.

Fig. 3 shows a plan view of a motor driven rheostat that may be used in my invention. A 45 reversible motor 34 drives a threaded shaft 28 through a speed reducing gear 32. A travelling nut 27 moves backward and forward along the threaded shaft depending on the direction of rotation. A moving contact 29 (not shown in this 50 figure but shown in Fig. 4) contacts the wires of a resistance winding 26 so that an adjustable amount of resistance is connected between the nut 27 and either end connection of winding 26.

Nut 27 has one surface shaped to engage two 55 rollers 30 and 31 which open limit switch con-

tacts **LL** and **HL** respectively when the nut reaches the ends of its travel.

The operation of the circuits of Fig. 4 will best be made clear from an assumed operation of the invention. A direct current supply circuit **L1** and **L2** furnishes energy for operating the circuits in this embodiment. Shunt field **23** of motor **24** and shunt field **31** of motor **34** are energized continuously by being connected across the supply lines. The armature of motor **24** is also continuously supplied through a circuit

L1—24—26—29—L2

Thus motor **24** turns continuously at a speed determined by the amount of resistance **26** included in the circuit by contact **29**. Assuming no cars at the dispatching floor, switches **TS1** to **TS4** will be open, relay coils **1C** to **4C** will be deenergized, and, assuming switch **15** open, coil **B** will be deenergized. Under these conditions, motor armature **34** will be energized through a circuit

L1—LL—B3—34—B5—36—L2

Thus motor **34** will turn in a direction to move travelling nut **27** to slow down motor **24**. If motor **34** is allowed to run long enough, limit contact **LL** will be opened by nut **27** and motor **34** will be stopped. At this time motor **24** will run at its lowest speed and the timing interval will have its greatest value.

Under the assumed conditions relay coil **1R** will be energized through the circuit

L1—1R—3R1—2R1—L2

Relay **1R** in picking up will energize coil **2R**

L1—2R—4R1—1R1—L2

Contact **2R1** will then open the circuit previously traced to coil **1R** and this coil will be deenergized. However, relay **1R** does not move immediately to the deenergized position as this relay, as well as **2R**, **3R** and **4R**, is provided with a time delay in opening of approximately 1 second. Therefore, about a second will expire before the armature of relay **1R** will move, and relays **1R** and **2R** will remain in the energized position during this time.

When the armature of relay **1R** does drop out, contacts **1R2** make a circuit to energize the coil of relay **3R**

L1—3R—1R2—2R2—L2

Relay **1R** also interrupts the previously traced circuit for coil **2R** which drops after its time element expires. During this interval the armatures of relays **2R** and **3R** remain in the energized position. When the armature of relay **2R** drops a circuit is made to energize the coil of relay **4R**

L1—4R—2R3—3R2—L2

Relay **2R** also interrupts the previously traced circuit for **3R** which drops out after a time delay. During this time, relays **3R** and **4R** are in the energized position.

When the armature of relay **3R** drops out, contacts **3R1** make a circuit to energize coil **1R**.

L1—1R—3R1—2R1—L2

It also interrupts the circuit to relay coil **4R** which drops out after a time delay. During this interval the armatures of relays **4R** and **1R** are in the energized position. Thus with no car at the floor, relays **1R** to **4R** continue picking up in a sequence requiring about four seconds for the cycle.

Assuming that while relays **1R** and **2R** are in the energized position that car **1E** arrives at the floor. The arrival of car **1E** closes switch **TS1** and relay **1C** is thereby energized

L1—1C—TS1—L2

The energized relay **1C** closes its contacts **1C1**, thus the coil of relay **B** becomes partially energized through resistor **10**.

L1—1C1—10—B—L2

This relay is one having adjustable pick up and drop out. Assume that at present it is adjusted so that at least two resistors **10** to **13** must be connected in parallel to energize the coil sufficiently to cause it to pick up.

Relay **B** therefore remains in the deenergized position. Relay **1C** closes a circuit to energize the coil of relay **1N**.

L1—1R3—2R4—1S1—1N—1C2—L2

Relay **1N** lights the signal light **1L** in car **1E**

L1—1L—1N4—L2

indicating to the car operator that his car is the next to leave the floor and to be prepared to leave on receipt of a start signal.

Relay **1N** also energizes coil **SS**.

L1—1N1—SS—L2

Relay **SS** partially energizes the coil of relay **1R**, through circuit **L1—1R—3R—SS1—L2** sufficient to prevent the relay armature dropping to the deenergized position.

Relay **SS** also partially energizes coils **3R** and **4R**.

L1—3R—40—SS3—L2

L1—4R—41—SS4—L2

but not sufficiently to cause their armatures to move to the energized position. As relay **1R** cannot now drop out, the progression of the cycle of relays **1R** to **4R** is stopped while relay **SS** is energized.

As time progresses, motor **34** continues to turn in a direction to insert slowly additional resistance of rheostat **26** into the armature circuit of motor **24**. Motor **24** is turning also but as time progresses it turns slower.

Assume now that car **2E** arrives at the dispatching floor. Switch **TS2** is closed by cam **8** of car **2E**. Relay **2C** becomes energized through circuit

L1—2C—TS2—L2

An additional circuit is now provided to coil **B**.

L1—2C1—11—B—L2

and the combined effect of the currents through coil **B** is sufficient to cause its armature to move to the energized position. Contacts **B3** and **B5** opening interrupt the previously traced circuit to motor armature **34** and contacts **B4** and **B2** establish another circuit

L1—HL—B4—34—B2—36—L2

in which the direction of the current flowing in armature **34** is opposite to that of the previously traced circuit. Motor **34** therefore reverses its direction of rotation and, as long as relay **B** is picked up, moves nut **27** in a direction to speed up motor **24**, and therefore to reduce the timing interval.

Assume now that switches **T1** and **T2** are operated simultaneously by cams **21** and **19**. Contact **T1** closes a circuit to relay **I**.

L1—T1—I—L2

Relay **I** establishes a self-holding circuit.

L1—I2—1S4—2S3—3S3—4S3—I—L2

As motor **24** continues to turn, contacts **T1** and **T2** return to their unoperated positions. That is, **T1** opens and **T2** closes. The closing of **T2** establishes a circuit to energize coil **1S**.

L1—I2—I1—I2—I1S—1C3—I—L2

Relay **1S** picks up and establishes a self-holding circuit.

L1—I2—I1—I2—I1S—I1C3—I—I2

It also interrupts the previously traced self-holding circuit to relay **I** which drops out. It also interrupts the pick up circuit to relay **1N** which drops out and it establishes a circuit to signal lamp **1L** through flicker relay **F**.

L1—I1—I1S—I1F—I1L—I2

Flicker relay **F** is of a type that opens and closes its contacts slowly. When the coil is energized contacts **F1** open after an interval which de-energizes coil **F** and lamp **1L**. After another interval contacts **F1** close and the sequence repeats. Flasher buttons for flashing lights operate on this principle. The effect of this is to cause the previous steady signal of lamp **1L** to become intermittent which serves as a signal to the operator of car **1E** that his waiting interval is ended and that he should leave the dispatching floor.

As coil **1N** has been deenergized, the circuit to relay coil **SS** is interrupted which releases the holding circuit to relays **1R** to **4R** previously described. Relay **1R** now drops out after a short time interval and relay **3R** picks up. (Previously described.) As we assumed car **2E** at the floor and relay **2C** energized, a circuit is now set up for energizing coil **2N**.

L1—2R5—3R3—2S1—2N—2C2—I2

which lights signal **2L** in car **2E** and picks up relay **SS** to again hold relays **1R** to **4R** in their present condition, that is, relays **2R** and **3R** in energized position and **1R** and **4R** in deenergized position.

If car **3E** had been assumed at the dispatching floor instead of car **2E**, the relay chain **1R** to **4R** would have continued until relays **3R** and **4R** were in the energized position at the same time at which time a circuit would have been completed to energize relay **3N**. Thus relays **1R** to **4R** constitute a selective mechanism so that only one car will have its "next" relay energized at a given time so that if several cars are at the dispatching floor only one will be selected to depart next.

Assume car **1E** operator has closed his door and left the dispatching floor opening switch **TS1** upon receiving the flashing signal to depart. This drops out relay **1C** which breaks the holding circuit to relay **1S** previously traced. This stops the intermittent signal in the car. The opening of contact **1C1** reduces the current through relay **B** to a point where it drops open. Motor **34** is again reversed and starts lengthening the next timing interval which action will continue until another car arrives at the floor to again pick up relay **B** through the current fed to the coil through contact **3C1** or **4C1** and resistor **12** or **13**.

From the foregoing it will be apparent that if one car is at the dispatching floor all the time and a second one there half the time, that motor **34** will slow down interval motor **24** half the time and speed it up half the time with a net effect over several periods of operation of no change in interval. Thus we may say that on an average there will be found one and one half cars at the dispatching floor.

It should also be evident that, if relay **B** is adjusted to pick up with the current through one resistor and drop out only on zero current, the interval will be shortened and cars dispatched from the floor at shorter intervals. A balance will occur when there is no car at the dispatching floor half the time and one car there half the time. Therefore, with this adjustment there will be found one car at the dispatching floor half the time if we assume that the cars make their trips and arrive back at this floor with the regularity with which they are dispatched from it, or we may say that on an average there will be found half a car at the dispatching floor. In practice no such regularity occurs but the timer automatically makes incremental adjustments of the timing interval in a direction to have this action occur considered over a period of time.

I have provided a switch **15**, adjustable cam **17** operating switch **T3**, a resistor **14**, and a contact of relay **B** with which means I can get any desired fraction of a car at the dispatching floor. For instance, I can have the cars receive a dispatch signal, considering the average, as soon as they arrive which is the shortest practical adjustment or I can have one car receive its dispatch signal just slightly ahead of the average arrival time of a second car so that I will have an average of one car at the dispatching floor all the time. The former condition will be described, I believe the operation of other combinations will be evident.

Assume now that switch **15** is closed and that cam **17** is set to open its associated contact **T3** 180° of rotation of shaft **22a** after contacts **T1** and **T2** return to their normal positions. Assume also that relay **B** is adjusted to pick up with the current of one resistor and to drop out with zero current. Under this latter condition with switch **15** open, I have pointed out that there will be or tend to be a car at the dispatching floor half the time. With switch **15** closed when relay **B** picks up an additional current is fed through coil **B** namely that flowing through resistor **14** in circuit.

L1—T3—I4—B1—I5—B—I2

When car **1E** now leaves the dispatching floor in response to the dispatch signal and its **C** relay drops out the circuit to relay **B** is not interrupted, being held in through the previously traced circuit and relay **B** remains in its energized position just as if another car were standing at the floor. It will stay in this position for 180° of rotation of timing shaft **22a** until contact **T3** opens or for half an interval. During this time the speed of the interval determining motor **24** will be increasing just as it would if there were an actual car at the dispatch floor. Thus the interval will be made shorter and shorter while the circuit **T3—I4—B1—I5** of what may be termed a "phantom car" is closed. A balance will occur when there is an actual or the "phantom car" at the floor half the time. When this occurs there will be no car at the floor half an interval and the "phantom car" half an interval, which also is no car,

or, theoretically the arriving car will be at the floor only long enough to pick up a C relay when it will receive a dispatch signal. In practice it will remain after its dispatching signal long enough to discharge and take on passengers before leaving which will in no way disturb the conditions that cause the giving of the dispatch signal at the time of arrival of the car.

I believe it will be evident that the angular position of cam 17 when changed will vary the time of the "phantom car" being at the floor and that the interval will be adjusted to give the dispatching signal sooner or later, depending on the direction of movement and amount.

I believe it will be evident that, with relay B adjusted to maintain one and one half cars at the floor and cam 17 adjusted to obtain half a car less (180° position previously described), there will be a net effect maintaining on the average one car at the floor.

Although I have illustrated and described only one specific embodiment of my invention, it is to be understood that modifications thereof and changes therein may be made without departing from the spirit and scope of my invention.

I claim as my invention:

1. A dispatching system for a plurality of elevator cars serving a plurality of floors comprising, a dispatching floor, a plurality of signal devices, one for each car, a timing device for giving dispatching impulses, and means responsive to the operation of the timing device and to the arrival and departure of the cars at the dispatching floor for operating the signal devices to give starting signals to the cars at intervals which will maintain on the average a predetermined number of cars at the dispatching floor.

2. A dispatching system for a plurality of elevator cars serving a plurality of floors, comprising a dispatching floor, a plurality of signal devices, one for each car, a timing device for giving dispatching impulses at predetermined intervals, means responsive to the arrival of the cars at the dispatching floor and to the operation of the timing device for operating the signal devices to give starting signals to the cars at predetermined intervals, and means responsive to the arrival and departure of the cars at the dispatching floor for causing the timing device to change the length of the predetermined intervals sufficiently to maintain on the average a predetermined number of cars at the dispatching floor.

3. A dispatching system for a plurality of elevator cars serving a plurality of floors, comprising a dispatching floor, a plurality of signal devices, one for each car, a timing device for giving dispatching impulses at predetermined intervals, means responsive to the arrival of the cars at the dispatching floor and to the operation of the timing device for operating the signal devices to give starting signals to the cars at predetermined intervals, and means responsive to a desired number of cars at the dispatching floor for causing said timing device to decrease its speed for one-half of the impulse interval and to increase its speed for the other half of the impulse interval and responsive to less than the desired number of cars at the floor to decrease the speed of the timing device for a greater portion of the interval than it increases the speed to thereby increase the length of the interval and thus make more cars available at the floor.

4. A dispatching system for a plurality of elevator cars serving a plurality of floors, comprising a dispatching floor, a plurality of signal de-

vices, one for each car, a timing device for giving dispatching impulses at predetermined intervals, means responsive to the arrival of the cars at the dispatching floor and to the operation of the timing device for operating the signal devices to give starting signals to the cars at predetermined intervals, and means responsive to the number of cars at said floor for controlling the timing device to affect the length of the next impulse interval; said means being responsive to a desired predetermined number of cars at said floor for causing the timing device to give equal successive impulse intervals between signals and responsive to more than said desired number of cars at said floor during one interval for causing the timing device to shorten at least two of said intervals.

5. A dispatching system for a plurality of elevator cars serving a plurality of floors, comprising a dispatching floor, a plurality of signal devices, one for each car, a timing device for giving dispatching impulses at predetermined intervals, means responsive to the arrival of the cars at the dispatching floor and to the operation of the timing device for operating the signal devices to give starting signals to the cars at predetermined intervals, and means responsive to no cars at said dispatching floor during one impulse interval for causing the timing device to increase the length of the impulse intervals between at least three consecutive impulses, regardless of the number of cars at said floor during the second interval.

6. A dispatching system for a plurality of elevator cars serving a plurality of floors, comprising a dispatching floor, a plurality of signal devices, one for each car, a timing device for giving dispatching impulses at predetermined intervals, means responsive to the arrival of the cars at the dispatching floor and to the operation of the timing device for operating the signal devices to give starting signals to the cars at predetermined intervals, and means responsive to a desired predetermined number of cars being at said floor during one interval for controlling the timing device to give the next impulse after the same interval as the last, said means being responsive to a less than said predetermined number of cars being at said floor during one of said intervals to cause the timing device to give a subsequent impulse after a longer interval, to thereby increase to said predetermined number of cars on the average the number of cars located at said floor, regardless of the round trip time of said cars.

7. A dispatching system for a plurality of elevator cars serving a plurality of floors, comprising a dispatching floor, a plurality of signal devices, one for each car, a timing device for giving dispatching impulses at predetermined intervals, means responsive to the arrival of the cars at the dispatching floor and to the operation of the timing device for operating the signal devices to give starting signals to the cars at predetermined intervals, and means responsive to operation of said first-mentioned mechanism for continuously adjusting the speed of the timing device to cause it to give impulses at intervals to keep a predetermined number of said cars on the average stationed at said floor, regardless of the round-trip time of said cars in serving said floors.

8. A dispatching system for a plurality of elevator cars serving a plurality of floors, comprising a dispatching floor, a plurality of signal devices, one for each car, a timing device for giv-

ing dispatching impulses at predetermined intervals, means responsive to the arrival of the cars at the dispatching floor and to the operation of the timing device for operating the signal devices to give starting signals to the cars at predetermined intervals, a rheostat for controlling the speed of the timing device, a motor for controlling the rheostat, an interval adjusting relay for reversing the direction of operation of the motor, and means responsive to the presence of a predetermined number of cars at the floor for energizing and deenergizing the relay to control the motor whereby the timing device will be controlled to give dispatching intervals of such length as to keep on the average a predetermined number of cars at the dispatching floor.

9. A dispatching system for a plurality of elevator cars serving a plurality of floors, comprising a dispatching floor, a plurality of signal devices, one for each car, a timing device for giving dispatching impulses at predetermined intervals, means responsive to the arrival of the cars at the dispatching floor and to the operation of the timing device for operating the signal devices to give starting signals to the cars at predetermined intervals, a circuit closing device operable by the timing device, a plurality of switches op-

erable by the arrival of the cars at the dispatching floor, one switch for each car, and means responsive to operation of the circuit closing device and to operation of the switches for causing the timing device to change the predetermined intervals to maintain on the average any desired fraction of a car at the dispatching floor.

10. A dispatching system for giving starting signals to a plurality of elevator cars operable past a plurality of floors, comprising a signal device for each of said cars, a timing mechanism for giving dispatching impulses at intervals, means for selecting the next car to receive a starting signal and for preventing the operation of more than one signal device at a time, said means comprising a plurality of chain connected relays adapted to operate repeatedly in a cycle; signal mechanism responsive to arrival of the cars at a predetermined floor, to operation of the selecting means, and to operation of the timing mechanism for operating the signal devices to give starting signals to the cars; and means responsive to operation of said signal mechanism for starting and stopping operation of said chain relays.

25 WILLIAM F. EAMES.
